CLAIM

The ornamental design for a personal alarm system with seatbelt cutter, glass breaker and striker-tipped cap, as shown and described.

DESCRIPTION

FIG. 1 is a front view of a personal alarm system with seatbelt cutter, glass breaker and striker-tipped cap, showing my new design.

FIG. 2 is a rear view thereof.

FIG. 3 is a top view thereof.

FIG. 4 is a bottom view thereof.

FIG. 5 is a right side view thereof.

FIG. 6 is a left side view thereof.

FIG. 7 is a front, bottom, and right side perspective view thereof.

FIG. 8 is a rear, bottom, and left side perspective view thereof.

FIG. 9 is a front view of the personal alarm system with seatbelt cutter, glass breaker and striker-tipped cap showing the striker-tipped cap removed to reveal the glass breaker.

FIG. 10 is a rear view thereof.

FIG. 11 is a right side thereof.

FIG. 12 is a left side view thereof.

FIG. 13 is a front, bottom, and right side perspective view thereof; and,

FIG. 14 is a rear, bottom, and left side perspective thereof.
